CHARLES S. WESTLAND, OF PROVIDENCE, RHODE ISLAND.

Letters Patent No. 65,711, dated June 11, 1867.

IMPROVEMENT IN STOP-MOTION FOR STEAM ENGINES.

The Schedule referred to in these Letters Patent and making part of the same.

TO ALL WHOM IT MAY CONCERN:

Be it known that I, CHARLES S. WESTLAND, of Providence, in the county of Providence, and State of Rhode Island, have invented a new and improved Stop-Motion and Regulator; and I do hereby declare that the following is a full, clear, and exact description thereof, which will enable others skilled in the art to make and use the same, reference being had to the accompanying drawings, forming part of this specification.

This invention relates to a method of stopping or slackening the motion of a pumping engine when from any cause the pressure has been suddenly removed; and the invention consists in providing a cylinder and piston, and connecting the same with the air-chamber of the pump, or to any other part where the pressure can be obtained, and with a valve in the steam pipe, whereby, through the action of a spring or some equivalent device the steam is shut off, or partially shut off, from the engine, as may be desired, when, from the bursting of the hose or other accident, the pressure is removed from the air-chamber, as will be hereinafter more fully described.

Figure 1 represents a view of my arrangement on a reduced scale, showing my cylinder connected with the air-chamber and with the rod of the throttle-valve in the steam pipe.

Figure 2 represents a vertical section of the cylinder and steam pipe on a larger scale, showing the different parts, and also a section of the pipe which connects the cylinder with the air-chamber.

Figures 3, 4, 5, and 6 represent a modification, whereby the same result is obtained in a different manner. Similar letters of reference indicate like parts.

A represents my regulating cylinder, which is connected with the air-chamber. B is the air-chamber. C is the pipe which connects the cylinder with the air-chamber. D is a piston in the cylinder A. E represents a spiral spring within the cylinder A, which is placed between the piston and the cylinder-head. F is the piston-rod. G represents the steam pipe. H is a throttle-valve in the steam pipe. J is a lever attached to the throttle-valve rod, by which the valve is operated. K is an arm attached to the steam pipe. It is double-slotted through its upper portion. The lever J is moved up and down in one slot, and the other slot holds an adjustable index or guide-plate, a, the position of which, on the arm K, determines the quantity of steam to be shut off. The end of the lever J passes through a slot in piston-rod F, as seen in the drawing. The guide or index a is adjusted to the arm by a thumb-screw, or in any other suitable manner. The arm is graduated so that the lines on it may indicate any pressure which it is desired to leave on the piston of the engine, or the speed to be retained when the engine is not entirely stopped. As the tendency of the spiral spring in the aperture is to press down the piston D, and consequently draw down the lever J and close the throttle-valve, I have shown in fig. 3 a modification by which the engineer may set the lever to regulate the pressure or speed of the engine. This is done by the stop C, which is made to slide on the piston-rod, and is fastened at any desired point by a set-screw. This stop prevents the rod from being drawn downward by the spring, as the spring bears upon the top of the cylinder-head. The piston-rod in this case is graduated by guide-marks instead of the arm. Instead of using a spring in the cylinder the down pressure on the piston D may be obtained by steam from the steam pipe. m represents a pipe which connects the upper portion of the cylinder with the steam pipe G. When the pressure below the piston D is removed the steam above it would force it down and close the throttle-valve H. It is to be understood that H is not the valve by which the steam is ordinarily let on to or shut off from the engine, and which is under the control of the engineer. The throttle-valve H is an additional valve in the steam pipe for the especial purpose before mentioned. It is immaterial whether the connection with the cylinder A is made with the lower portion of the air-chamber, or with its upper or air portion, or with the pump-barrel itself, as the pressure in either case produces the same result.

The operation of the arrangement will be readily understood from the drawing. The pressure on the under side of the piston in the cylinder A (when the engine and pump are in operation) will be the same as the pressure in the air-chamber, communication between them being free, and the pressure by the spring, or otherwise, upon the upper side of the piston is designed to be about equal to it, so that when the pump is in operation there would be about an equilibrium in the pressure on the piston D. The pressure of the spring may be increased or diminished by the cap N, which forms the top of the cylinder, bearing down the spring on to the piston and increasing its tension, or by unscrewing it the tension is diminished. In this condition, with the pressure on the piston nearly balanced, and the engine and pump in motion, if the hose should burst, or the

supply of water should be exhausted, or any other accident whereby the pressure on the piston D was removed or materially diminished, and in consequence of which it became necessary to stop the engine or to check its speed, the superior pressure on the upper side of the piston would force it down and close the throttle-valve, or partially close it, according as the engineer had set the lever J. The steam engine might be allowed to move with the steam gate or valve open while a new piece of hose could be coupled. When this was done the pressure would be sufficient to immediately raise the piston D and let on the full pressure of steam to the engine. In the modifications shown in the figs. 4, 5, 6, and 7, the same result is obtained by winding up a spring on to a cylinder, as shown in fig. 5. The action of the spring is communicated to the piston by a ratchet-wheel and pawl, the ratchet-wheel being held in position by a dog, as seen.

I am aware that there are other ways and methods by which the pressure of the water may be made to operate upon a valve in the steam pipe than those herein shown and described.

My invention, as before stated, consists in stopping and regulating the action of the steam engine and pump, by the movement of a piston in a cylinder which shall act upon the valve in the steam pipe, when, from any cause, the pressure is removed from the air-chamber.

Having thus described my invention, what I claim as new, and desire to secure by Letters Patent, is—

1. The combination of the air-chamber B, pipe C, regulating cylinder A containing the piston D and spiral spring E, piston-rod F, with or without the sliding-stop e and graduations, steam pipe G containing the valve H, lever J, double-slotted graduated arm K holding the adjustable index a, and pipe m, substantially as described for the purpose specified.

2. The arrangement of the spring on the cylinder communicating action to the piston by a ratchet-wheel and pawl, as shown in fig. 5, said ratchet-wheel held in position by a dog, substantially as described for the purpose specified.

The above specification of my invention signed by me this 7th day of February, 1867.

CHARLES S. WESTLAND.
